HENRY P. CLAUSEN, OF MOUNT VERNON, NEW YORK, ASSIGNOR, BY MESNE ASSIGNMENTS, TO WESTERN ELECTRIC COMPANY, INCORPORATED, A CORPORATION OF NEW YORK.

TELEPHONE-EXCHANGE SYSTEM.

1,210,602.

Specification of Letters Patent.

Patented Jan. 2, 1917.

Application filed September 8, 1915. Serial No. 49,476.

To all whom it may concern:

Be it known that I, HENRY P. CLAUSEN, a citizen of the United States, residing at Mount Vernon, in the county of Westchester and State of New York, have invented certain new and useful Improvements in Telephone-Exchange Systems, of which the following is a full, clear, concise, and exact description.

10 This invention relates to telephone exchange systems, and more particularly to such systems of the central energy type.

In telephone exchange systems now in use, considerable difficulty is experienced in handling calls for engaged subscribers' lines. Calling for a line and finding it engaged, a subscriber must call again, and it frequently happens that before reaching the desired line, a subscriber may call several times.

20 This takes up the time of an operator and is of considerable annoyance to the subscriber.

It is an object of this invention to overcome these difficulties, and to provide a telephone exchange system in which a subscriber calling another subscriber and finding the line engaged, may then ask the operator to call when the desired line is not engaged.

A link circuit is provided by means of which an operator may plug into the jacks 20 of the calling and called lines without telephonically connecting the two lines. The talking strands of this link circuit are preferably normally open. With this link circuit associated with each line, both subscribers may 35 call for and be connected to other lines without in any way affecting the link circuit, but as soon as both lines become idle, apparatus in the link circuit functions to close the talking strands thereof and to furnish a signal 40 to the operator. Preferably only a few link circuits of this character are furnished in each operator's position, the interconnection of lines ordinarily being handled by means of regular link circuits.

45 For a more complete understanding of this invention, reference should be made to the accompanying drawing, wherein is illustrated a telephone exchange system showing one embodiment of the invention and comprising the usual subscribers' stations A and B and a cord circuit C located at a central office for interconnecting the subscribers' stations. For convenience, only two subscribers' lines are shown in the drawing, but it is 55 to be understood that many more such lines

terminate at the central office. Cord circuit D, shown in the drawing, is of the usual bridged-impedance, two-conductor type, and is ordinarily used in connecting two lines for conversation. It is intended that only a few cord circuits, similar to C, will be provided at each operator's position, while the majority of the cord circuits at an operator's position will be similar to D.

Suppose that subscriber B is connected by 65 means of cord circuit D with another subscriber whose line terminates at the central office, and that subscriber A initiates a call, desiring to be connected with subscriber B; the operator, in response to the line signal 70 of subscriber A, answers by inserting the answering plug of a cord circuit similar to D. Finding that subscriber A desires to be connected with subscriber B, the operator, testing and finding B's line busy, so advises 75 A. A may then request that he be called when B's line becomes idle and hang up his receiver, in which case the operator withdraws the answering plug of the cord circuit from the jack of A's line, and connects plug 80 5 of cord circuit C with a multiple jack of A's line and plug 6 of this cord circuit with a multiple jack of B's line.

The insertion of plug 5 into a multiple jack 85 of A's line does not alter the condition of any apparatus associated with A's line or with that end of cord circuit C. The insertion of plug 6 into a multiple jack of B's line causes the operation of slow release relay 7, due to a flow of current from battery 90 in a cord circuit D connected with another jack of B's line. The operation of relay 7 causes the operation of slow release relay 8 over a circuit from battery, through contact 10 of relay 7, and right-hand winding of relay 8 to ground. Relays 7 and 8 remain in operated condition as long as the plug of cord circuit D is inserted in a jack of B's line. As soon as this plug is removed, however, relay 7 releases, thereupon causing the 95 operation of relays 15 and 16. The energizing circuit of these two relays may be traced from battery, through contact 11 of relay 7, contact 17 of relay 8, the windings of relays 15 and 16 in parallel, contact 18 of 100 relay 8 and contact 19 of relay 20 to ground. The operation of relays 15 and 16 closes the talking strands of cord circuit C, and causes the operation of relays 21 and 22 and the 105 cut-off relays associated with lines A and 110 B.

B. The operation of relay 21 causes the operation of relay 23 over an energizing circuit from battery, through contact 25 of relay 8, winding of relay 23, and contact 30 of relay 21 to ground. Relay 23 upon operating, completes a locking circuit for itself, which may be traced from battery, through contact 31 of listening key 32, contact 33 and winding of relay 23, and contact 30 of relay 10 21 to ground. The operation of relays 21 and 22 completes a locking circuit for relays 15 and 16 from battery, through contact 11 of relay 7, contact 34 of relay 22, the windings of relays 15 and 16 in parallel, contact 15 35 of relay 21, and contact 19 of relay 20 to ground. The operation of these relays 21 and 22 closes their respective contacts 36 and 37. Relays 21, 22 and 23 being operated, close a circuit for supervisory lamps 20 40 and 41. This circuit may be traced from battery, through lamps 40 and 41 in parallel, contacts 36 and 37 of relays 21 and 22 in parallel, contact 42 of relay 23, and interrupter 43 to ground. The completion of 25 this circuit causes the supervisory lamps 40 and 41 to flash intermittently. This serves as a signal to the operator that both lines A and B are now not busy. The operator may now actuate listening key 32, thereby 30 opening the locking circuit of relay 23 which disconnects the interrupter from the circuit of lamps 40 and 41, and substitutes ground at the back contact 47 of relay 23 so that supervisory lamps 40 and 41 burn steadily. 35 The operator then actuates ringing keys 45 and 46 to send ringing current over lines A and B to signal these two subscribers. The subscribers, in responding to the ringing of their respective call bells, remove the receivers from the switchhooks, thereby causing the operation of relays 48 and 49 which open the circuits of supervisory lamps 40 and 41. After completing the conversation, 40 subscribers A and B restore their respective receivers to the switchhooks, whereupon relays 48 and 49 release to complete the circuits of supervisory lamps 40 and 41, which now become lighted to furnish disconnect signals. The operator, observing these two 45 signals, removes plugs 5 and 6 from the jacks of lines A and B, whereupon all apparatus returns to normal condition, as shown in the drawings.

It will be remembered that when plug 55 5 of cord circuit C was inserted into the multiple jack of A's line, the condition of the apparatus associated with A's line and with that end of cord circuit C was not altered. While cord circuit C was connected with the 60 multiple jacks of lines A and B, and at the same time the cord circuit D was connected with a jack of B's line and a jack of another line, subscriber A might initiate a call, desiring to be connected with another 65 subscriber whose line terminates in a central

office. The operator observing the line signal associated with A's line, would insert the answering plug of a cord circuit similar to D into the answering jack of A's line and complete the connection to the wanted subscriber's line. The insertion of the answering plug of a cord circuit similar to D into the answering jack of A's line, causes the energization of relay 20 of cord circuit C, completing a circuit through 70 the left-hand winding of relay 8. If, while the subscriber A was talking to another subscriber, the cord circuit D is disconnected from the jack of B's line, relay 7 would release, but no circuit would be completed for relays 15 and 16 because contact 19 of relay 20 is open. When the answering plug of the cord circuit similar to D is removed from the answering jack of A's line, relay 20 releases thereupon completing a circuit for relays 15 and 16. After the operation of these relays 15 and 16, the other apparatus in the cord circuit C functions, as hereinbefore described, to complete the talking strands of cord circuit C and 80 to cause the flashing of supervisory signals 40 and 41. The operator may then signal subscribers A and B as hereinbefore.

It will be observed that the insertion of 85 plugs 5 and 6 into the multiple jacks of lines A and B does not alter the electrical condition of the sleeve strands of the jacks. Consequently these lines are not made busy, due to cord circuit C. It will furthermore be observed that by utilizing the telephone exchange system embodying applicant's invention, a waiting subscriber may call and be called without affecting the waiting connection in any manner whatever. Relays 7, 8 and 20 have hereinbefore been referred to as slow-release relays. Relay 8, however, is considerably slower in releasing than relays 7 and 20. This is necessary in order that relays 21, 22 and 23 may operate after the operation of relays 15 and 16 and before relay 8 releases. Cord circuit D is of the ordinary type and is believed to require no description. It is to be understood that this cord circuit D will be provided with a listening and a ringing key, as is the 100 usual practice.

What is claimed is:

1. In a telephone exchange system, subscribers' lines terminating in a plurality of switching terminals at a central office, a link circuit thereat having coöperating switching terminals connecting two of said lines, a second link circuit having switching terminals for connecting a third line and one of said connected lines and adapted to 110 be connected therewith without altering the electrical condition of the switching terminals of said lines, a signaling device associated with the second link circuit, and apparatus associated with the second link 115 120 125 130

circuit operating when the first link circuit is disconnected from said busy line to cause the operation of the signaling device.

2. In a telephone exchange system, subscribers' lines terminating at a central office, a link circuit thereat connecting two of said lines, a second link circuit for connecting a third line with either of said connected lines, said second link circuit having normally open talking strands, a signaling device for the second link circuit, apparatus associated with said second link circuit preventing the closure of the talking strands thereof when one end of the second link circuit is connected to a busy line, apparatus associated with the second link circuit operating to close the talking strands thereof when the busy line becomes idle, and means actuated upon the operation of the second mentioned apparatus for causing the operation of the signaling device.

3. In a telephone exchange system, subscribers' lines terminating in a plurality of switching terminals at a central office, a link circuit having coöperating switching terminals connecting two of said lines, a second link circuit having switching terminals for connecting a third line and one of said connected lines and adapted to be connected therewith without altering the electrical condition of the switching terminals of said lines, a supervisory signaling device associated with each end of said second link circuit, and apparatus associated with said second link circuit operating when said first link circuit is disconnected from said busy line to cause the operation of said supervisory signaling devices.

4. In a telephone exchange system, subscribers' lines terminating in a plurality of switching terminals at a central office, a link circuit having coöperating switching terminals connecting two of said lines, a second link circuit having switching terminals for connecting a third line and one of said connected lines and adapted to be connected therewith without altering the electrical condition of the switching terminals of said lines, a supervisory signaling device associated with each end of said second link circuit, a circuit-interrupting device, and apparatus associated with said second link circuit operating when said first link circuit is disconnected from said busy line to include said supervisory signaling devices and said circuit-interrupting device in circuit, whereby said signaling devices are caused to furnish intermittent signals to an operator.

5. In a telephone exchange system, subscribers' lines terminating at a central office, a link circuit thereat for interconnecting said lines and adapted to be connected with two busy lines to establish a waiting connection therebetween, said link circuit having normally open talking strands, apparatus associated with said link circuit preventing the closure of the talking strands while said lines are busy, and apparatus operating when said busy lines become idle to close the talking strands.

6. In a telephone exchange system, subscribers' lines terminating at a central office, a link circuit thereat interconnecting two of said lines, a second link circuit for interconnecting a third line and one of said connected lines, said second link circuit having normally open talking strands, two relays in said second link circuit operated upon the connection of said second link circuit with one of said connected lines, one of said relays releasing upon the disconnection of said first link circuit from the line connected with said second link circuit, a third relay operating upon the release of said last mentioned relay to close breaks in the talking strands of said second link circuit, a signaling device for the second link circuit, an operating circuit for the signaling device, and means actuated upon the operation of the third relay for closing the operating circuit.

7. In a telephone exchange system, subscribers' lines terminating at a central office, a link circuit thereat interconnecting two of said lines, a second link circuit for interconnecting a third line and one of said connected lines, said second link circuit having normally open talking strands, two relays in said second link circuit operated upon the connection of said second link circuit with one of said connected lines, one of said relays releasing upon the disconnection of said first link circuit from the line connected with the second link circuit, a third relay operating upon the release of said last mentioned relay to close breaks in the talking strands of the second link circuit, a signaling device for the second link circuit, interrupter mechanism, and relay mechanism actuated upon the operation of the third relay for including the interrupter mechanism in circuit with the signaling device.

In witness whereof I hereunto subscribe my name this 7th day of September, A. D. 1915.

HENRY P. CLAUSEN.
